THREAD CUTTING DEVICE FOR THIMBLES

Filed April 8, 1927

FIG. 1.

FIG. 3.

FIG. 2.

FIG. 4.

FIG. 5.

FIG. 7.

FIG. 6.

Inventor,
Maxime Feer
by Herbert W. Jenner
Attorney

UNITED STATES PATENT OFFICE.

MAXIME FEER, OF LONDON, ENGLAND.

THREAD-CUTTING DEVICE FOR THIMBLES.

Application filed April 8, 1927. Serial No. 182,012.

This invention has relation to thimbles and has in contemplation more especially a thread-cutting device forming an integral part of the thimble which can be used when the said thimble is on the finger and which is so contrived that it is guarded or protected against catching or causing damage accidentally to the user or wearer or to the workpiece which is being sewn.

10 My present invention has for its object the production of a simple and cheaply constructed thread-cutting device for thimbles possessing advantages in point of efficiency and durability in that the cutting device is circular thereby enabling the thread to be cut from any side of the thimble; further the said cutting device is located at the top of the thimble and is protected by suitable guards located around the upper periphery 15 of the thimble.

According to this invention the thimble is provided with or has secured to it, at the upper or forward end of the body part or at or approximately at the junction of the body 20 and the dome or end, a circular cutting device, the edge of which projects beyond or outwardly from the body and a series of dovetailed or similar fingers or guards which embrace or project beyond the cutting edge, 25 and are spaced apart at suitable intervals to expose sufficient portions or segments of the cutter to cut a thread but to prevent also the cutting edge from cutting the work piece or the user.

30 The cutting device may be formed in one with the thimble if the latter is made of a suitable metal or it may be a separate ring or disc secured to the thimble in any appropriate manner.

35 The dovetailed or similar guard fingers may be formed in one with either the body or the dome of the thimble or both or they may be carried on a separate ring or band.

With the above mentioned objects in 40 view, the invention consists in the novel construction of a thread-cutting device for thimbles used in sewing and combination of parts hereinafter described, illustrated in the accompanying drawings, and specified 45 in the claims hereto appended; it being understood that various changes in the form, proportion, sizes, and other minor details of construction within the scope of the claims may be resorted to without de-

parting from the spirit or sacrificing any 55 of the advantages of the invention.

To more fully comprehend the invention reference is directed to the accompanying drawings forming a part hereof and of which:

Fig. 1 is an elevation illustrating a thimble provided with the thread-cutting device.

Fig. 2 is a plan view of Figure 1.

Fig. 3 is a sectional elevation of Figure 1.

Fig. 4 is a sectional elevation of a modified arrangement of thread-cutting device;

Figs. 5, 6, and 7 are fragmentary plan views showing the dovetailed or other shaped guards for the cutting device.

Referring more particularly to the several views of the drawings, wherein like reference letters designate corresponding parts throughout the several views, A is the cutting device, B the dovetailed guard fingers, C the body of the thimble and D the top or dome.

Referring to the embodiment of the invention shown in Fig. 1 the cutting device A is formed in one with the body of the thimble.

This arrangement is suitable when the body of the thimble is made of steel or some other metal which can be sharpened to provide an efficient cutting edge.

In this example the upper end of the thimble body C is bent over to project outwardly and is sharpened to provide or constitute the cutting device A. The dovetailed or similar guard fingers or protectors B are formed on the dome or top D. These fingers are spaced apart around the outer periphery of the top or dome as shown in Figure 2. They project over the cutting device B and are bent over as shown. They thus serve to provide openings between them to 95 guide the thread to be cut, to prevent the possibility of contact of the cutting edge with the hand of the user or with the work and at the same time serve to secure the top or dome D of the thimble to the body 100 part C. The top or dome of the thimble may be secured, however, to the body by other means, and the fingers B may only serve to prevent accidental contact with the cutting device. Conversely the cutting device A may be formed in one with the top or dome D and the guard fingers B may be formed on the body part C of the thimble.

105

Referring now to the arrangement shown in Fig. 4 the cutting device A in this example, is made separate from the thimble and comprises a disc ring or it may be a 5 ring of steel or other appropriate metal, which is placed on the upper end of the thimble body C. This disc or ring A is of slightly larger diameter than the end of the thimble body so that it projects beyond the 10 thimble walls. This disc or ring A may be secured to the thimble body by soldering or the like, or it may be secured in position by the dovetailed or similar guard fingers B. The guard fingers B are, in the present 15 case formed in one with the top or dome D. The dome or top D may be secured to the ring or disc A by any appropriate means or it may be secured as shown by providing a rim or flange C¹ on the upper end of the 20 thimble body C and bending the ends of the fingers B over to embrace the cutting device A and to pass under the flange or rim C¹.

As a modification the dovetailed or similarly shaped guard fingers B may be formed 25 in part on the body C and in part on the top or dome D in which case the fingers B on the body C would be placed alternately with the fingers on the top or dome D.

The guard fingers B in place of being 30 formed on the body C or on the top of dome D may be formed on a ring or band which may be secured to the thimble body in any appropriate manner.

In Figure 5 a guard B for the fingers 35 from the thread cutting edge A is shown which is of dovetailed formation or having that configuration and it will be seen in the figure in question that the outer edges of this guard are closer together and that the 40 taper inner faces are adapted to retain the thread against the edge of the cutting device.

Although the above mentioned dovetailed shaped guard is the preferred arrangement

it will be understood that a guard formed 45 as shown in Figures 6 and 7 may be employed to enable a ready insertion of the thread.

This invention may be embodied also in open ended or tailors' thimbles in which case the cutting device A is conveniently in the form of a ring which may be made in 50 one with or may be secured to the body of the thimble in any appropriate manner. In this case also the guard fingers B may be carried on a separate band or ring or if the cutting ring A is separate from the thimble, 55 the fingers B may be formed on the thimble.

In use any one of the exposed portions or sections of the blade is pressed against the thread to be cut by a movement of the finger on which the thimble is carried. 60

Having now described my invention what I claim as new, and desire to secure by Letters Patent is:—

1. A thimble having a tubular body portion, and a top plate covering one end of the body portion, one of the said parts being provided at its periphery with a series of fingers spaced apart and projecting laterally around the body portion of the thimble, and a thread-cutting device having a sharp edge which projects laterally of the smaller end of the body portion of the thimble within the spaces formed between the said fingers. 65

2. A thimble having a tubular body portion, and a top plate covering one end of the body portion, one of the said parts being provided at its periphery with a series of fingers spaced apart and projecting laterally around the body portion of the thimble, and a thread-cutting disk secured between the 70 body portion and top plate and having a sharp edge which projects laterally of the smaller end of the body portion within the spaces between the said fingers. 75

In witness whereof I affix my signature.
MAXIME FEER.
